(57) **CLAIM**

The ornamental design for a water sport board, as shown and described.

DESCRIPTION

FIG. 1 is a top plan view of the water sport board;

FIG. 2 is a top front perspective view thereof;

FIG. 3 is a front left side perspective view thereof;

FIG. 4 is a top rear perspective view thereof;

FIG. 5 is a side elevation view thereof; and,

FIG. 6 is a bottom plan view thereof.

The broken lines are for environmental purposes only and form no part of the claimed design.
